UNITED STATES PATENT OFFICE

2,432,979

FABRICATED WOOD STAGING PLANK

P Bob Attwell, Seattle, Wash.

Application August 29, 1945, Serial No. 613,277

1. Claim. (Cl. 304—38)

1
This invention relates to a built up or fabricated wood staging plank of the type commonly used in connection with various kinds of scaffolds by workmen such as painters, carpenters and the like.

An object of this invention is to provide a fabricated wood staging plank that is much lighter in weight and at the same time much stronger than the usual wood staging plank of the same over all cross sectional size and length.

Another object is to provide a fabricated wood staging plank that is not expensive to construct, that is efficient and durable in use and that is waterproof.

Boards, such as two by twelve inch wooden planks of any desired length, are ordinarily used as staging planks on scaffolds to support workmen such as painters, carpenters and the like. These planks are ordinarily twelve to sixteen feet long and are heavy for the workmen to handle. Also these long heavy planks add considerable to the weight on the scaffold and the margin of safety of the longer wooden planks, when they are supported from points near their ends, is not as high as it should be.

A sixteen foot fabricated wood staging plank made in accordance with this invention is about one-third the weight of an ordinary clear fir staging plank of the same length, width and thickness and will withstand about three times as great a load when it is supported from its two ends and the load is applied midway of its length.

It is therefore an object of this invention to provide a staging plank that is safer for the workmen to use than is the ordinary staging plank.

Other objects of this invention will be apparent from the following description taken in connection with the accompanying drawings.

In the drawings

Figure 1 is a plan view of a staging plank constructed in accordance with this invention.

Fig. 2 is a longitudinal section of the same taken on broken line 2—2 of Fig. 1.

Fig. 3 is a longitudinal section taken on broken line 3—3 of Fig. 2.

Fig. 4 is a cross section on a larger scale than the other figures taken on broken line 4—4 of Fig. 3.

Like reference numerals designate like parts throughout the several views.

This staging plank comprises three longitudinally extending parallel frame members 10, 11 and 12; two transverse end headers 13 and 14 and two sheets of plywood 15 and 16 which form

2
the two flat sides of the plank. The longitudinal frame members 10 and 11 are positioned at the sides of the plank and the frame member 12 substantially medially thereof. Preferably the longitudinal frame members 10, 11 and 12 and the transverse end headers 13 and 14 are pieces of relatively light weight strong wood, such as spruce, about three quarters of an inch thick and about one and three quarters inches wide.

10 The sheets 15 and 16 which form the faces of the plank may be three ply fir plywood one quarter of an inch thick with the grain of the two outside plies of each sheet running lengthwise of the sheet.

15 The strength of this staging plank can be increased about thirty percent by securely gluing to the inner face of each side frame member 10 and 11, medially between its two ends a one-half by one and three fourths inch spruce wood reinforcing strip 17. Each reinforcing strip 17 is

20 preferably about one third of the length of the plank. The reinforcing strips 17 add some weight to the plank and for this reason preferably are omitted from planks not intended for heavy service.

25 Preferably short cleats 18 are securely glued to opposite sides of the medial frame member 12 near the two ends thereof. These cleats cooperate with the frame member 12 to provide solid wood of sufficient width so that a transverse hole 19 at least three quarters of an inch diameter may be bored through the plank adjacent each end thereof medially of its width.

30 Preferably the end portions of the medial frame member 12 are transversely bowed slightly as shown in Figs. 1 and 3 to displace the cleat carrying ends of said frame member 12 far enough from the medial axis of the plank so that when the holes 19 are bored midway between

35 the two sides of the plank they will be bored partly in the cleats 18 and partly in the member 12 and there will be no danger of the holes 19 cutting through the sides of the member 12 and leaving openings through which water could enter.

40 In assembling this plank preferably waterproof glue is used and all of the parts are securely glued together under pressure in such a manner as to provide a hollow plank that will exclude water, that is light in weight, and that is very strong. Preferably the wood from which these planks are made is treated to render it highly resistant to moisture, weather conditions and fungus.

45 The holes 19 facilitate handling the planks and may receive pins or bolts which help to pre-

3

vent displacement of the planks on their supports, or these holes may receive cables or flexible fastening members by which the planks may be secured to their supports. These planks are light enough so that a workman standing on one of said planks can, with his foot, readily move another of said planks along the scaffold means on which it is supported to a new position. This saves time and labor. Also these planks, being stronger than ordinary wooden staging planks of the same size, are safer to use.

These planks are substantially the same thickness as ordinary staging planks and can be used on all types of scaffolds, swinging or otherwise, where ordinary staging planks are used.

The medial rib 12 provides support to the plywood sheets 15 and 16 midway between the two sides of the plank and makes it possible to use plywood sheets of one quarter inch thickness.

Obviously changes in this staging plank may be made within the scope of the following claim.

I claim:

A fabricated wood staging plank of light weight and great strength comprising a relatively long narrow thin frame formed of two parallel side frame members, a medial frame member and two head pieces all adhesively secured together; two short cleats adhesively secured to opposite sides of said medial frame member near the respective ends thereof providing increased thickness at the location of said cleats; and two thin plywood sheets adhesively secured to opposite

6 sides of said frame, said plywood sheets serving as a tension and a compression member on the top and bottom sides of said frame respectively when the plank is positioned on spaced apart supports and subjected to a load; said plank having a hole therein adjacent each end midway between the two sides of the plank, each hole extending through the two plywood sheets and through the medial frame member and cleat 10 therebetween.

P BOB ATTWELL.
